UNITED STATES PATENT OFFICE.

LYBERAT HUWÝLER, OF GOLDAU, SWITZERLAND.

RAILWAY BAGGAGE OR GENERAL-GOODS CAR.

1,419,675.

Specification of Letters Patent. Patented June 13, 1922.

Application filed January 27, 1920. Serial No. 354,362.

To all whom it may concern:

Be it known that I, LYBERAT HUWÝLER, a citizen of the Swiss Confederation, residing at Goldau, Canton Schwyz, Switzerland, 5 have invented new and useful Improvements in a Railway Baggage or General-Goods Car, for which the following is a specification.

The present invention relates to a new 10 and improved railway baggage or general goods car destined for the transport of goods, cattle and horses.

The primary object of the invention is to provide self-locking means to secure the skid 15 in its position for use.

Another object consists in providing such means for locking the skid which are simple in construction and easy to be actuated even in the dark and by unexperienced operators.

20 Other objects of the invention relate to the provision of minor parts cooperating with the elements above noted and to details of construction all of which will be more clearly set forth in the following specification.

25 With the above objects in view the invention resides in the parts and combinations of parts hereinafter described and particularly set forth in the claims appended hereto.

30 In order that my invention may be clearly understood, I have shown the same in the drawings by way of an example.

Fig. 1 shows a goods-car in a side elevation.

35 Fig. 2 shows half of a car in a section on line A—B of Fig. 1.

Fig. 3 is a front view of the skid applied to a car.

40 Figs. 4 and 5 show one of the end pieces of the guides for the skid in different positions.

Fig. 6 is a top view of one end of the skid arranged in its guides.

45 Figs. 7 and 8 show sections on the lines C—D and E—F of Fig. 5 illustrating the arrangement of the tongue to guide the skid.

In the drawings 1 denotes the floor of a goods car which is provided with two sliding side doors 2 in the well known manner. 50 On the lower side of the floor 1 in line with the side doors 2 there are two horizontal guide-ways 4, 5 arranged parallel to each other transverse to the car and firmly fixed

to the beams 12 of the car frame. Each guide-way is provided at each end with a 55 guide piece 6. On the guide-ways 4, 5 and in horizontal grooves of the pieces 6, in line with the said guide-ways 4, 5 run rollers 7 arranged at the four corners of a movable skid 8. The skid 8 comprises an iron frame 60 covered by wooden boards, it is strongly built and its length corresponds to the breadth of the car. To secure the skid in its position below the floor 1 I arrange two hooks 9, 10 of unequal length both hooks 65 being fixed to a common shaft 11 which is journaled in the beams 12 of the car-frame. On each side of the car the shaft 11 is provided with a handle 15 by means of which the hooks 9, 10 may be brought out of engagement with the ledges 17 of the skid 8. The ledges 17 are parallel with each other 70 and their upper surfaces are inclined downwardly toward the ends of the skid 8. To limit the movement of the shaft 11 I arrange 75 two abutments 14 (Fig. 3) on the beam 12 between which an arm 16 of the shaft 11 plays. The hooks 9, 10 are held and brought in engagement with the skid 8 by a spring 53, they slide over the ledges 17 when the 80 skid 8 is moved on its guide-ways 4, 5. From the ledges 17 the hooks 9, 10 drop behind the faces of the ledges as soon as the skid 8 assumes its proper position. In each guide piece 6 there is a horizontal groove in 85 line with the guide-ways 4, 5 and a branched-off guide groove 18 leading upwardly and ending in a short horizontal groove 19. To bring the the skid 8 in the position for use it is withdrawn from the side of the car from 90 beneath the floor 1. The rollers 7 near the front end viz near the end of the person drawing the skid leave the pieces 6 but the rollers 7 on the hind end of the skid pass from the horizontal grooves into the 95 branched-off guide-grooves 18, 19 of the guide pieces 6. The arrangement of the grooves 18, 19 are such that the hind end of the skid 8 is flush with the floor 1 as soon as the rollers 7 enter the grooves 19 to ensure 100 a convenient instep of the car (as shown in Fig. 2 in dotted lines). To make the rollers 7 on the hind end of the skid 8 to pass from the horizontal grooves of the pieces 6 into the grooves 18 I arrange on each piece 105 6 a switch 20. The switch 20 comprises a

double-armed lever which is journalled on a pivot 22. One arm 23, forming a tongue projects into the horizontal groove and forms a part of the guide groove for the rollers 7, the other arm 21 of the lever is provided with a slot 24 into which the end 26 of a second double-armed lever projects. The lever 26, 28 is rotatably mounted in the guide piece 6 and projects with a curved arm 28 in the path of the skid 8. If the skid 8 rests beneath the floor 1 (Fig. 5) the arm 28 abuts against the lower side of the skid 8 and the switch 20 assumes the position as shown in Fig. 4. The tongue 23 takes the position shown in which it guides the hind roller 7 into the branched-off groove 18. The skid 8 resting on arm 28 secures the tongue 23 in its position. If the skid 8 is withdrawn into its position for use shown in Fig. 2 by dotted lines, the rollers 7 at the fore part of the skid leave the pieces 6 the rollers 7 at the hind end pass into the grooves 18 and ascend until they bear against abutments 30 resting on springs in the front part 32 of the guide pieces 6. As soon as the skid 8 leaves the arm 28 the tongue 23 swings upwards, the weight of the parts 21, 26 exceeding that of the parts 23, 28. To lock the skid 8 in the loading position I provide on each piece 6 a double armed lever 39, 40 rotatably mounted in said piece 6 by means of a bolt 41. The arm 39 projects into the path of the roller 7 in the groove 19 and is held in the position shown in Fig. 4 by means of the weighted arm 40. A third arm 45 is fastened to the bolt 41 against which a lock bolt 43 abuts. The bolts 43 on each side of the car are fixed to a rod 44 journalled in bearings and provided at each end with a handle 42. In the position shown in Figs. 3 and 4 the bolts 43 lock the levers 39, 40 in the position shown and the skid 8 is secured in its position. To free the skid 8 the handles 42 are turned in such a manner that the arm 39 leaves the groove 19. By moving the skid 8 in its position for use it is automatically secured against accidental displacement when loading or unloading the car. To bring the skid back into its position below the floor 1 the arms 39 are turned out of the way of the rollers 7 by rotating the rod 44 and the skid 8 is moved against the car. The rollers 7 on the hind or upper part of the skid 8 descend the groove 18 and the skid may be pushed below the floor. The rollers 7 may pass the switch 20 at the opposite car side the tongue 23 being in its uppermost position (see Fig. 4). While the skid 8 is moved into the guides 4, 5 the hooks 9, 10 slide on the ledge 17 until they fall over the hind end thereof. The skid 8 is now secured in its proper position the ends of it projecting just far enough from the sides of the car to be used as a second tread. Rollers 52 arranged at the front ends of the

pieces 6 facilitate the moving of the skid 8.

From the foregoing it is obvious that the skid may be withdrawn from any side of the car, in no position it loses the connection with the car and in no way interferes with the general arrangement and design of the car.

It frequently happens that the train moves somewhat whilst the loading or unloading takes place. I provide therefor rollers 51 75 on the small sides of the skid in order that the latter may easily follow the car preventing thereby damage.

Foldable railings may be provided which may be used for unloading cattle or I may 80 arrange rails at the side walls of the car which could be used for railings in case of need.

Various details of construction for instance the means for locking the skid in its 85 position etc. may be varied without departing from the spirit of the invention.

Although I have described the preferred form of construction I wish it understood that various details of construction may be 90 changed without departing from the spirit of the invention.

What I claim and wish to secure by Letters Patent is:

1. A skid, rollers thereon, at its ends, 95 guides in which the skid is mounted for movement, guide pieces at the ends of the guides, each having an inclined guide way and a branched-off guide way at the upper portion of said inclined guide way, switches 100 to direct the skid from the horizontal to the inclined guide ways, and operating means for the switches automatically actuated by the rear rollers of the skid, when the latter is drawn outwardly, to cause the 105 rear end of the skid to be elevated.

2. A skid, rollers thereon, at its ends, 110 guides in which the skid is mounted for movement, guide pieces at the ends of the guides, each having an inclined guide way and a branched-off guide way at the upper portion of said inclined guide way, switches to direct the skid from the horizontal to the inclined guide ways, and yieldable buffers 115 against which the rear rollers of the skid strike, when the rear end of the skid is elevated.

3. A railway car comprising in combination a skid, rollers on said skid, two guide-ways fixed beneath the car floor in line with 120 the side doors of the car, a guide piece at each end of each guide way, each guide piece having a horizontal groove in line with the corresponding guide way and an ascending groove branching-off from said horizontal groove, switches to lead the rollers from the horizontal to the ascending groove, each switch comprising a tongue projecting into the path of the rollers, means to set said switch by gravity and by the skid and means 130

to lock the switch when in use said means comprising a double-armed lever, one arm projecting into the path of the said roller, a shaft rotatably mounted and provided 5 with handles, locking arms fixed to said shaft co-acting with arms of the said double-armed levers substantially as described.

In testimony whereof I affix my signature in presence of two witnesses.

LYBERAT HUWÝLER.
